UNITED STATES PATENT OFFICE.

NILS H. ANDERSON, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,155,634.

Specification of Letters Patent.

Patented Oct. 5, 1915.

Application filed April 27, 1908. Serial No. 429,407.

To all whom it may concern:

Be it known that I, NILS H. ANDERSON, a citizen of the United States, residing at Hartford, in the county of Hartford and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines of that class wherein the type carriers are provided with two or more types, 15 and wherein the platen is normally held in position to receive imprints from one or more sets of type, the type carrier and the platen being relatively shiftable to enable the platen to receive imprints from the other 20 set or sets of type.

One of the objects of the present invention is to provide means for guiding the shiftable part which will be of simple construction, and which will perform its functions 25 without producing noise.

Another object is to provide guiding mechanism for shiftable platen carriages of typewriting machines such that the opposite ends of the platen will be moved through 30 equal distances when shifted and the face of the platen will always be maintained in parallelism with the faces of the types and also in the same line at the different printing points.

35 Other objects will be in part obvious and in part pointed out hereinafter.

The invention accordingly consists in the features of construction, combinations of elements and arrangement of parts which 40 will be exemplified in the construction hereinafter set forth, and the scope of the application of which will be indicated in the following claims.

In the accompanying drawings, wherein 45 are illustrated several of the various possible embodiments of my invention, Figure 1 is a view in side elevation of my improved mechanism. Fig. 2 is a rear view thereof looking from the right of Fig. 1. Fig. 3 is a plan view of the mechanism shown in Figs. 1 and 2, the carriage being omitted in the interest of clearness, and a portion of the structure being shown in section. Figs. 4 and 5 show a portion of the carriage and

the manner in which it is mounted upon 55 the shifting and guiding mechanism, and also showing the position of the parts when the carriage occupies different shifted positions. Figs. 6, 7 and 8 are diagrammatic views illustrating the positions occupied 60 by the centers of the shift rail and the shifting levers when the carriage occupies its normal, as well as its shifted positions, with respect to the types. Fig. 9 is a view taken substantially on line 9—9 of Fig. 1 looking 65 in the direction of the arrow, certain parts being shown in section. Fig. 10 is a view upon an enlarged scale showing the adjusting devices for the lower ball rail of the platen carriage. Figs. 11 and 12 show a different 70 embodiment of the mechanism for guiding the shift rail, the parts being shown in two positions. Figs. 13 and 14 show another embodiment of the mechanism for guiding the shift rail. Fig. 15 shows another embodiment thereof, and Fig. 16 shows still another embodiment of this mechanism. Fig. 17 is a conventional illustration of a plurality of type bars.

Similar reference characters refer to similar parts throughout the several views of the drawings.

Referring now to the drawings 1 indicates a portion of the frame of a typewriting machine, and 2 represents a table or bed 85 adapted to support a set of printing members which, in the present instance, are constituted by straight thrust type bars, one of which is shown at 3. The type bars are provided with a plurality of printing characters or types, in the present instance three in number, and are projected forwardly upon the supporting bed against the platen by means of actuating mechanism not herein shown.

4 represents the platen carriage which is constituted by side members 5 and 6 respectively, connected by longitudinally extending members 7. The platen carriage 4 is provided with the usual paper roll 8, in front of which and connected to the side walls of the carriage is provided a platen 9, which in the present instance is a thin strip of metal having a vertically disposed face for receiving the types and a rear curved 100 face which lies in contact with the paper roll. The rear portion of the paper carriage slides vertically and longitudinally 105

with respect to an abutment 10, which is formed, in the present instance, by an up-standing portion or horn of a tie-rod 11, which extends transversely of the machine beneath the bed, and is anchored in the front wall of the machine at 12.

The platen carriage 4 is provided with two rails 13 and 14 respectively, which are spaced apart as shown, and which extend 10 between the side pieces 5 and 6 of the platen carriage. These rails are provided with oppositely disposed grooves 15 and 16 for receiving sets of balls 17 and 18, which travel in correspondingly shaped grooves 19 and 20 provided in a vertically shiftable supporting rail 21 interposed between rails 13 and 14 of the platen carriage. In the present instance, the upper rail 13 of the platen carriage is permanently fixed thereto, while 20 the lower rail 14 may be adjusted toward or from the fixed rail, by means of adjusting screws 22 as clearly shown in Fig. 10 of the drawings, clamp screws as at 23 being provided for holding the adjustable rail in fixed 25 position after adjustment. The object of providing for this relative adjustment of rails 13 and 14 of the platen carriage, is to enable these parts to be initially adjusted with respect to the shiftable rail upon which 30 the platen carriage travels during letter spacing so that no lost motion will exist therein, and so that any lost motion which might occur from time to time, due to wear, may be effectively taken up.

35 Two balls, in the present instance, are provided in each pair of opposing grooves of the upper and lower rails of the platen carriage, and those of the shiftable rail, and in order to prevent the balls from moving 40 beyond their proper running distance, centrally located stop pins 24, are provided, and holders 25, are provided at the ends of the rail, said holders, in the present instance, comprising sheet metal devices let into rail 45 21 and bent over into the groove thereof, as shown at the right hand side of Fig. 9, and the right hand side of Fig. 3. For the centrally located stop pins 24, holders similar to those shown 25 may be provided, 50 such construction being, in some respects, preferable, for the reason that they can not be readily jarred out of operative position.

Depending from either end of the shift rail 21, upon which the platen carriage 55 travels, are shift links 26 and 27 respectively, said links being pivotally connected to the ends of the rail by means of trunnion screws 28 and 30 threaded into the ends of the rail, as clearly shown in Figs. 3 and 9 60 of the drawings. The opposite ends of links 26 and 27 are connected respectively to arms 31 and 32, which extend from a rock shaft 33 suitably journaled in the lower portion of the frame of the machine, and which 65 is rocked in opposite directions by shift

mechanism not herein shown, which may be connected thereto by means of an arm 34 fixed upon said rock shaft.

A balancing spring 35 may be employed to counterbalance the weight of the platen carriage, which is normally to be held in a central position to enable the platen to receive imprints from the middle set of types. It will be understood that an oscillation of rock shaft 33 in either direction will, 75 through the links 26 and 27, effect a shifting movement of the platen carriage in opposite directions from its normal central position, so that the platen will be moved to such positions as will enable it to receive imprints from either the upper or lower set of types, and that the counterbalancing spring 35 will be of such tension as will tend to maintain the platen carriage in its normal central position. 80

85 In this embodiment of my invention the faces of the types shown at 36, 37 and 38 in Fig. 1 of the drawings, are shown as disposed in a common vertical plane, the platen 9 being shown with its operative face in a 90 plane which lies parallel with the plane occupied by the type faces, and in order that the platen may travel in a substantially vertical line when moved to its shifted positions and be maintained always in a plane parallel to the faces of the type, I have provided improved guiding mechanism for the shiftable platen frame, which I shall now proceed to describe.

95 Pivots connected to the ends of the rail 21 and, in the present instance, swiveled upon trunnion screws 28 and 30, are arms 40 and 41 respectively, each of which slides in a pivotally mounted trunnion. These trunnions, which are shown at 42 and 43 respectively, are carried by lugs or upstanding portions 44, which project from a fixed portion of the frame of the machine, in the present instance, said lugs being formed upon laterally extending portions 45 of the 100 center tie-rod. The opposite ends of arms 40 and 41 are pivotally connected at 46 and 47 with forwardly extending oscillating arms 48 and 50 respectively, which are fixed upon and extend forwardly from a balancing rock shaft 51. This rock shaft is journaled near either end in the upstanding portions 44 of the center tie. 110

115 Having thus described the construction of this embodiment of my invention, the operation thereof may now be understood. When the rail 21 is shifted either up or down by means of links 26 and 27, which are connected to rock shaft 33, arms 48 and 50 mounted upon rock shaft 51 through their 120 connection with arms 40 and 41 respectively, are swung in the arc of a circle, the radius of which bears such relation to the swinging radius of those portions of arms 40 and 41 125 between the trunnions and the shiftable rail, 130

which latter radius is constantly varied by reason of the fact that said latter arms may slide in either direction in their trunnions, that the center 52 of said rail will lie in the same vertical plane when in any of the shifted positions. In other words, the arc which the oscillating arms 48 and 50 describe, and that described by arms 40 and 41, are so changed relative to each other that the shiftable rail will move in an almost mathematically straight line or a vertical plane whenever said rail is lifted or depressed. The curve through which the platen travels from one printing point to the other is so slight as to be negligible. The manner in which the movement of the platen in parallelism with the faces of the type is effected, is illustrated diagrammatically in Figs. 6, 7 and 8, wherein the line X—Y, which varies but a few ten-thousandths of an inch from a straight line, is indicative of the plane in which the shiftable rail moves, the points C, U and L showing the central, upper and lower positions of the shiftable rail, B the center of the rock shaft 51, T the trunnion in which the rail carrying arms slide, and A the arc described by the ends of the arms 48 and 50 respectively. It is, therefore, seen that the carriage while pivoted to the frame of the machine, is provided with compensating means whereby the three printing points occupied by the platen in its shifted positions, are in the same straight line.

In the embodiment of the platen carriage-guiding means shown in Figs. 11 and 12, the shiftable rail upon which the carriage is mounted and upon which the same slides for letter spacing, is shown at 53, and as in the embodiment above described, is connected to the shift mechanism by means of links, one of which is shown at 27. Arms 54 are pivotally connected to either end of rail 53, said arms being supported and sliding at their opposite ends in trunnions 55 journaled in the frame of the machine. To arms 54 are connected arms 56, which are fastened to a balancing shaft 57, which is supported in the frame of the machine. When rail 53 is shifted either up or down, the arms 56 cause the arms 54 to slide in trunnions 55, whereby said rail moves in the substantially straight line G—H.

In the embodiment of the invention shown in Figs. 13 and 14, the carriage rail 58 is connected to shifting mechanism by the links 60, said rail being pivotally connected to arms 61 supported and sliding on stubs 62. Arms 61 are connected by pivots 63 to arm 64 fastened to a balancing shaft 65 supported in the frame of the machine. In Fig. 13 the parts are shown in central position, and in Fig. 14 they are shown in an upper position, the rail having moved in a vertical direction along a line I—J, and being con-

trolled in such movements by arms 64, while arms 61 slide backward and forward on studs 62.

In Fig. 15 the parallel movement described in the first of the above embodiments of my invention is shown applied to a plain or round rail which supports the carriage. In this modification, one of the links connecting the carriage with the shift is shown at 66, said links being pivotally connected with the trunnioned arms 67 which are connected to the oscillating arms of the balancing shaft.

In the embodiment of my invention shown in Fig. 16, the parallel movement of the structure is similar to that shown in Fig. 15, and the parts are similarly numbered. The links for connecting the stem with the shift are shown at 66 connected to the pivot 68. The outer ends of arms 67 are made circular in contour, as shown at 70, and serve as trunnions at two points for the rail 71, upon which the platen carriage travels through the interposition of trucks 72, which run upon rail 71, a take-up roller 73 being provided which engages the lower part of the shift rail. This device moves the platen carriage vertically substantially parallel with the faces of the types in a manner similar to that shown in the diagrams illustrated in Figs. 6, 7 and 8, so that the three printing points are in the same straight line.

It will accordingly be seen that I have provided mechanism which is well adapted to attain, among others, all the ends and objects above enumerated in an extremely simple, yet efficient manner. The guiding mechanism for the platen carriage, in each of the embodiments of the invention above described, operates not only to maintain the platen in absolute parallelism with the plane occupied by the faces of the types at the printing points, but also insures that both ends of the platen carriage will move equal distances when the same is shifted either upward or downward from its normal central position. The adjustment given the lower rails of the platen carriage insures that no lost motion shall exist between the same and the shiftable rail, thus eliminating any chance of noise occurring from the operation of these parts during the shifting or letter spacing movements of the carriage. A further advantage accruing by reason of the present construction resides in the fact that all impacting parts are eliminated, rendering the entire shifting operation capable of being effected substantially without noise.

While I have shown my invention as applied to typewriting machines of the above type, it will be obvious that the same is readily adaptable to machines of other types.

As many changes could be made in the above construction and many apparently widely different embodiments of this inven-

tion could be made without departing from the scope thereof, it is intended that all matter contained in the above description or shown in the accompanying drawings shall be interpreted as illustrative and not in a limiting sense.

Having described my invention what I claim as new and desire to secure by Letters Patent, is:

10 1. In a typewriting machine, in combination, a shiftable part, shifting mechanism therefor, a relatively fixed part, and pivotally mounted connecting means between said shiftable part and fixed part to compel a 15 movement of the shifted part to three different printing positions lying in the same plane.

2. In a typewriting machine, in combination, a set of type-bars each being provided 20 with a plurality of type, and a platen, one of which is shiftable to change the relative position of the type and platen for printing different case characters, means for supporting and shifting the shiftable part, and 25 means pivotally connected with the shiftable part for compelling a movement thereof to shifted positions equally distant from the other part.

3. In a typewriting machine, the combination with the type bars, each of which carries a plurality of types, and a platen, of means for compelling the platen to move in a substantially vertical plane when shifted, comprising a shift rail, a rock shaft, intermediate connecting links, and swinging arms connected with the rail and with the frame of the machine.

4. In a typewriting machine, the combination with the type bars, each of which is 40 provided with a plurality of types, and a platen shiftable in a direction transverse to its length, of a rock shaft journaled in a fixed portion of the machine, and means connected with said rock shaft and with 45 said platen for compelling a movement of the latter to a shifted position in the same plane parallel to the plane occupied by the faces of the types when the latter are projected to the printing point.

5. In a typewriting machine, the combination with the type bars each of which carries a plurality of types, and a platen carriage shiftable with respect to said types, of swinging means connected with the platen 55 carriage and adapted to guide the same in its shifting movements, and means for varying the radius of said swinging means whereby the platen carriage will be moved in a substantially straight line.

6. In a typewriting machine, the combination with the type bars, each of which is provided with a plurality of types, and a platen carriage shiftable in a direction transverse to its length for different case 65 printing, of a plurality of swinging mem-

bers pivotally connected with the platen carriage and adapted to guide the same in its shifting movements, and means for changing the swinging radius of said members whereby the platen carriage may move in 70 a direction substantially parallel to the faces of the types.

7. In a typewriting machine, the combination with the type bars, each of which is provided with a plurality of types, and a 75 platen carriage shiftable in a direction transverse to its length, of a shiftable rail upon which the platen carriage is mounted and upon which the same travels for letter spacing, and a pair of swinging members 80 pivoted to said rail and adapted to guide the same, pivotal supports for said swinging means located intermediate their ends and in which said members may slide during their swinging movements, and means for 85 causing said members to slide in said supports when said rail is moved to shift the platen carriage, whereby the swinging radius thereof will be so varied that the rail will be moved in a substantially straight 90 line.

8. In a typewriting machine, the combination with the type bars, each of which carries a plurality of types, a vertically 95 movable platen frame carrying a platen, of means for effecting a vertical movement of the platen frame in a plane parallel to the faces of the types when projected to the printing point, comprising a pair of swinging members connected with the platen frame, pivotal supports for said swinging members in which they are adapted to slide, and means connected with said swinging members for changing the swinging radius thereof whereby the platen frame will be 105 compelled to move in a substantially vertical plane.

9. In a typewriting machine, the combination with the type bars, each of which is provided with a plurality of types, and a 110 shiftable platen carriage, of means for effecting a movement of the platen carriage in a plane parallel to the faces of the types when projected to impression, comprising a pair of swinging members connected with the platen carriage, trunnions in which said swinging members are adapted to slide, and means connected with said swinging members for causing the latter to slide in their trunnions when the platen carriage is shifted, whereby the swinging radius of said members will be so varied that the platen carriage will be compelled to move in a 120 plane substantially parallel to the faces of the type.

10. In a typewriting machine, the combination with the type bars, each of which is provided with a plurality of types, and a shiftable platen carriage, of means for compelling a movement of the platen carriage 125

in a vertical plane when shifted, comprising a pair of arms connected with the platen carriage, a pivotal support for each of said arms in which it is adapted to slide, a rock 5 shaft journaled in a fixed portion of the framing of the machine, and arms mounted upon said rock shaft and connected with said first named arms adapted when said rock shaft is rotated to cause said first 10 named arms to slide in their pivotal supports whereby the swinging radius thereof will be so varied that the platen carriage will move in a vertical plane.

11. In a typewriting machine, the combination with the type bars, each of which is provided with a plurality of types, and a platen carriage, of a shiftable rail upon which the platen carriage is mounted and upon which it is adapted to ride for letter 15 spacing, and means pivotally connected with said rail which is adapted to compel a movement thereof along a substantially straight line when the same is shifted to change the disposition of the platen with respect to 20 the types.

12. In a typewriting machine, the combination with the type bars, each of which carries two or more types, and a vertically movable platen frame carrying a platen, a vertically 25 movable rail upon which the platen frame is mounted and upon which it rides during its letter spacing movements, of means for effecting a vertical movement of the platen frame whereby the platen will be 30 carried in a plane parallel to the faces of the types when they are projected to impression, comprising a pair of swinging members one of which is connected to said rail at each end thereof, a pivotal support for 35 each of said members with which it is relatively slidably, a rock shaft, and a connection interposed between each of said members and said rock shaft adapted when said rail is moved to change the swinging radius of 40 said members, whereby said rail will be compelled to move in such plane as will move the platen in a plane substantially parallel to that occupied by the faces of the types when 45 they are projected to impression.

13. In a typewriting machine, the combination with the type bars, each of which carries two or more types, and a platen carriage, of a shiftable rail upon which the platen rail is mounted and upon which the 50 same rides for letter spacing, a pair of swinging members one of which is connected with said rail at either end thereof, a trunnion for each of said members in which it is adapted to slide, and means for causing said 55 members to slide in said trunnions when said rail is moved, whereby the swinging radius of said members will be so varied that the rail will be moved in a substantially straight line.

14. In a typewriting machine, the combi-

nation with the type bars, each of which is provided with a plurality of types, and a platen carriage, a shiftable rail upon which said carriage is mounted and upon which the same rides for letter spacing, a rock shaft 70 independent of the shifting means journaled in a fixed portion of the machine, and an intermediate operative connection between said rock shaft and said rail whereby the same is moved in a plane substantially parallel to the plane occupied by the faces of the types when they are projected to the printing point.

15. In a typewriting machine, the combination with the type bars, each of which is 75 provided with two or more types, and a platen frame carrying the platen, of a vertically movable rail upon which the said platen frame is mounted and upon which it slides for letter spacing, a rock shaft journaled in a fixed portion of the framing of the machine, and intermediate operative connections extending from either end of said rail and said rock shaft adapted to compel a movement of the former in a vertical 80 direction when the same is shifted to different printing positions in the same vertical plane.

16. In a typewriting machine, the combination with the type bars, each of which carries two or more types, and a shiftable platen carriage, of a vertically shiftable rail upon which the platen carriage is supported and upon which the same travels for letter spacing, a swinging member connected 95 with each end of said rail, a trunnioned support for each of said swinging members and in which said member is slidably, a rock shaft supported in a fixed portion of the framing of the machine, and intermediate 100 operative connections between said rock shaft and said swinging member for changing the swinging radius of the latter when said rail is moved to shift the platen, whereby said rail will be compelled to move in a 105 substantially straight line.

17. In a typewriting machine, the combination with the type bars, each of which carries a plurality of types, and a platen carriage adapted to be held in such position that the platen will be adapted to receive impressions from the middle set of types, a shiftable rail upon which the platen carriage is mounted and upon which it rises for letter spacing, of a swinging support for said rail, and means for changing the swinging radius of said swinging support whereby said rail will be moved in a substantially straight line and the platen moved in a direction substantially parallel to the plane occupied by the faces of the types when they are projected to the printing point.

18. In a typewriting machine, the combination with the type bars, each of which carries three types, and a platen carriage 120

adapted normally to be supported in such a position that the platen may receive impressions from the middle types of the type bars, of a vertically shiftable rail upon which the platen carriage is mounted and upon which it rides for letter spacing, a swinging support for said rail, a rock shaft with which said swinging support is connected, portions of said swinging support being relatively movable whereby the swinging radius thereof may be so varied that said rail will be caused to move along a substantially straight line when shifted and the plate will be moved in a plane substantially parallel to that assumed by the faces of the types when they are projected to the printing point.

19. In a typewriting machine, the combination with the type bars, each of which carries a plurality of types, and a vertically shiftable platen frame adapted to be supported in such position that the platen may receive impressions with the middle types of the type bars, of a vertically shiftable rail upon which the platen carriage is mounted and upon which it rides for letter spacing, means for compelling a movement of the platen carriage in a substantially vertical plane when said rail is shifted, comprising a pair of arms, one of which is connected to each end of said rail, a trunnioned support for each of said arms with which it has a sliding engagement, a rock shaft journaled in a fixed portion of the framing of the machine, and a pair of arms extending from said rock shaft, each of which is connected with one of said first mentioned arms.

20. In a typewriting machine, the combination with the type bars, which carry three sets of types, of a platen carriage adapted to be supported normally in such position that the platen will receive members from the middle set of types, a rail upon which the platen carriage is supported and upon which the same rides during its letter spacing movement, means for moving said rail upward and downward from a normal central position, and swinging arms connected with each end of said rail for compelling an equal movement of either end thereof when the same is moved upward or downward from its normal central position, said arms also operating to compel a movement thereof in a substantially straight line.

21. In a typewriting machine, the combination with the type bars which carry three sets of type, of a vertically shiftable platen carriage adapted to be supported in such position that the platen will receive impressions from the middle set of types, a vertically shiftable rail upon which the platen carriage is mounted and upon which the same slides for letter spacing, means connected with the opposite ends of said rail

for shifting the same upward and downward from a normal central position, a rock shaft, and intermediate operative connections between said rail and said rock shaft for compelling an equal movement of the opposite ends of said rail when the same is shifted and a movement thereof in a plane substantially parallel to that occupied by the faces of the types when they are projected to impression.

22. In a typewriting machine, the combination with the type bars which carry three sets of type, a vertically shiftable platen frame adapted to be supported in a normal central position whereby the platen will normally receive impressions from the middle set of types, a vertically shiftable rail upon which the platen carriage is supported and upon which it slides for letter spacing, a link depending from each end of said rail and pivotally connected therewith, the opposite ends of said links being connected with the shifting mechanism, and means for compelling an equal movement of the opposite ends of said rail when said links are actuated to move said rail upward or downward from its normal central position, comprising a rock shaft journaled in a fixed portion of the framing of the machine, a pair of arms one of which is extended from either end of said rock shaft, an arm pivotally connected with each of said first mentioned arms and similarly connected with said rail at each end thereof, and a pivotal support for each of said latter arms in which it is adapted to slide.

23. In a typewriting machine, the combination with the type bars, each of which carries a plurality of types, and a shiftable platen carriage, of a shiftable rail upon which said platen carriage is mounted and upon which it rides for letter spacing, and means for compelling equal movements of the opposite ends of said rail comprising a rock shaft journaled in a fixed portion of the framing of the machine, and a pair of pivotally connected arms interposed between said rock shaft and said rail at the opposite ends of those parts, one arm of each of said pairs being fixed upon said rock shaft and one end of the other arm of each of said pairs having a pivotal connection with said rail.

24. In a typewriting machine, in combination, a part adapted to be shifted for printing different case characters, a swinging arm connected therewith at one end and pivotally supported at its opposite end, and means associated with one of said parts for changing the swinging radius of said arm.

25. In a typewriting machine, in combination, a part adapted to be shifted when different case characters are to be printed, means for guiding the said part during its

shifting movement comprising a swinging arm connected therewith, and means associated with said arm for changing the swinging radius of said arm whereby the shifted part lies in the same plane in all of its shifted positions.

26. In a typewriting machine, in combination, a part adapted to be shifted, means for guiding the said part during its shifting movement comprising swinging arms at either end of said part connected to permit a change in the swinging radius of one of each of said part of arms.

27. In a typewriting machine, in combination, a part adapted to be shifted, a swinging member connected therewith, means adapted to actuate said swinging

member as said part is shifted and means to move the pivot of said member during the movement of said shiftable part. 20

28. In a typewriting machine, the combination with a relatively fixed part, of a shiftable part having means pivotally connected therewith, said connection comprising compensating means whereby said shiftable part may move in a substantially straight line. 25

In testimony whereof I affix my signature, in the presence of two witnesses.

NILS H. ANDERSON.
